FAN BLADE AND ITS FORMATION

William E. Morrison, Torrington, Conn., assignor to The Torrington Manufacturing Co., Torrington, Conn., a corporation of Connecticut

Application December 17, 1947, Serial No. 792,130

5 Claims. (Cl. 170—159)

1

This invention relates to fan blades and their formation, and more particularly to certain improvements in both the sectional shaping and plan contour of the blades of propeller type fans, the improvements being ideally adapted to fans for relatively high air delivery or volume within relatively low pressure ranges, such as so-called attic fans. The present improvements are, however, broadly adapted for use in numerous installations requiring low pressure, high volume air propellers.

The greatly increased extent of use of large diameter propellers for ventilation purposes generally, and particularly in the field of so-called attic fans, has directed much experimental work to the end of providing a more quiet and efficient type of fan for this purpose. Many of the air propellers heretofore offered to the trade exhibit a lower efficiency in this field of usage, than should be expected in view of experience with other propellers in a variety of other fields. The present invention accordingly has as a major object, the improvement of efficiency of fans for the general purposes noted, at the same time realizing a more quiet propeller.

Somewhat more particularly stated, the present improvements objectively realize a more efficient fan for low pressure, high volume work, by application of what is herein designated as the induction principle, hereinafter more fully explained.

In furtherance of the object last above expressed, additional important objective features of the design include the use of a relatively small center disc or spider for the purpose of blade mounting; a design to permit a maximum blade angle, conducing to large open passages of great area between the blades, and a relatively narrow blade root portion, further conducing to a substantial section of air channel between the adjacent blade root portions, in keeping with the induction theory above noted.

A further and highly important object of the present improvements is attained in an improved blade formation such that a propeller formed of these blades will exhibit a high mechanical efficiency in the low pressure range of its performance curve.

The foregoing and numerous other objects will more clearly appear from the following detailed description of a single preferred embodiment of the invention as applied to a propeller fan for use in various ventilation fields, for example, as in an attic fan of 36" diameter, the description being predicated on a fan of this

size and type, and best understood when considered in connection with the accompanying drawing, in which:

Fig. 1 is a plan view of the pressure or delivery face of the improved propeller fan and center disc, only two blades being shown for clearness, one thereof being broken away;

Fig. 2 is a front elevation of a four blade fan with present improvements, being the most usual embodiment;

Fig. 3 is a plan view of a blade blank, with the view taken of the pressure face of the blade after blanking, but before forming, hence in unpitched relation;

Fig. 4 is a fragmentary section the location of which, in a formed blade, is along line 4—4 of Fig. 3;

Fig. 5 is a further section, and being fragmentary in nature, this section being located, in a formed blade, along line 5—5 of Fig. 3;

Fig. 6 is a fragmentary sectional view, the location of which in a formed blade, is indicated by line 6—6 of Fig. 3; and

Fig. 7 is a transverse section taken on a curved plane parallel to but somewhat inwardly of the peripheral edge of the blade, the location thereof being designated by line 7—7 of Fig. 1, this figure including, in dotted lines, an edge portion of the center disc in order to portray, diagrammatically, the pitch of the blade.

Referring now by characters of reference to the drawing, the propeller fan is comprised of a selected small plurality of blades formed of a suitable sheet material, such as sheet steel or aluminum, the blades being attached at equiangular intervals to and about a spider of any suitable form, exemplified in the present disclosure as a planar center disc 10. The blades are mounted to provide a pitch angle of the order of 45 degrees in the example shown. The disc 10 is apertured at 11 for a hub or other suitable shaft mounting element (not shown). The number of blades is of course optional, there usually being two, three or four in a fan of the general type illustrated and for the fields of usage described. Each blade is generally indicated at 12 and in the example shown, is secured to the center disc 10 through a pair or more of

50 security tabs 13 and 14 indicated on the blank of Fig. 3, the extremities of which are formed to result in attachment lugs 15 and 16, apertured at 17 for the reception of attachment bolts 20 engaging suitable apertures (not shown) in the center disc 10. No exhaustive description of this blade attachment feature is

included herein since it constitutes per se, the subject of a copending application Serial No. 711,273, filed November 21, 1946, by this applicant. It may be noted, however, that the tabs 13 and 14 are bent along lines 21 and 22 so that the body of each tab lies outwardly from and at a distinct angle to the face or faces of the center disc, and each tab forms therewith, a short tubular passage 23 adjacent the center disc and directed toward the medial region of the root portion of the blade.

Proceeding now to a description of the nature, contour and formation of the body of the blade proper, it should be noted that the apparent difference in blade width between Figs. 1 and 3, is due to the relatively high pitch preferably imparted to the blade in mounting same on the center disc, and derived by the angularity and location of the attachment tabs 13-14. Since it is felt that the construction and formation of the blade will be best understood by reference to Fig. 3 wherein the blade is observed in plan and in unpitched relation, as if lying flat, it will be noted as including a leading edge 24 which is generally radial but nevertheless widely curved, on an almost uniform arc on a large radius. Proceeding outwardly from the root region, the leading edge 24, through a rounded corner 25, which would otherwise appear as an apex, merges into a widely arcuately formed peripheral margin 26 which is or may be of substantially regular curvature although possibly deviating to a very minor extent from a regular curve. The line or edge 26 is brought inwardly in a rounded corner 27, thence merging into the trailing margin or edge 30 of the blade. The edge 30 is approximately radial and is shown as being straight.

It will appear that if the lines 30 and 24 were to be continued inwardly they would intersect in or near the axis of revolution, or perhaps slightly outwardly thereof. It will be obvious to those involved with the design of propeller blades that the rounded cornering 25 and 27, as is of itself well known, conduces to quietness of operation. But for such elimination of true apices, the blade in plan would generally resemble a triangle modified by rounding of one side such as 24, shown as being a uniformly curved line on a radius of 14 inches, and the base such as 26. If the blade be considered as an uppermost blade, such triangle or quasi-triangle would be viewed in inverted relation, and by reason of the root portion should be considered as further modified in that it is frustrate in what becomes the root portion of the blade. This shaping, as will appear from the drawing, results in an unusually narrow root portion which conduces to the provision of a maximum path of air ingress in the regions of the blade roots, and over the periphery of the center disc. The proportions of the blade as viewed in plan or outline, are further such that the blade width in or just inwardly of its periphery preferably substantially equals or even exceeds the length of its active surface on a radius drawn from the center of revolution. Thus the fan is of a distinctly wide blade type.

Over considerably the greater part of the area of its pressure or forward face each fan blade is of nearly flat, or of concave aspect, with the exception of a minor portion hereinafter noted in the trailing area of the blade. For consideration of blade formation, specifically its various sectional shapes, it may be considered as divided into three areas as viewed on its pressure or forward face. The direction of rotation is indi-

cated by the large arrow near the periphery of the complete blade of Fig. 1. Thus the curved leading margin 24 together with a part of the peripheral edge 26 and a forming line AB, bounds a quasi-triangular leading area A-25-B. The line AB, located at an angle of 20 degrees to a radius through point B, may be considered as the median of a channel directed from the root region near point A outwardly to the periphery of the blade at B. On the leading side of the line AB, the pressure face of the fan is concave on forwardly projecting radii, and on the trailing side of line AB, as will be described, there is a large practically flat area ABC, which may be very slightly curved on very large forward radii. In the area of which line AB is a trailing boundary line, there is a forming curvature on forward radii, these radii being approximately, but without restriction, of the order of fourteen inches. Thus the area A-25-B constitutes a portion of the wall of a cylinder of that radius, and merges gradually and smoothly into the area ABC. This formation results in a channel on the forward face of the blade which slopes in the direction of air flow as will appear, from the blade root about point A, and thence extends toward the peripheral region in the general direction of air movement across the blade when the fan is in motion.

In the preferred construction as shown, a second preferably rectilinear forming line is indicated at CB, located at 16 degrees to the radius through point B, the lines AB and CB being of converging trend toward the periphery of the blade, as will be noted. The generally triangular space between forming lines AB and CB constitutes an intermediate, approximately flat triangular area or zone. The formation curvature of the area just beyond line CB, is preferably, for best results, in a typical fan blade of 36" diameter, on forwardly projected radii of the order of ten inches. Thus it will now appear that the area bounded by BCD constitutes a portion of a cylinder having a radius of ten inches, and that the area ABC merges smoothly and gradually into BCD. This part cylindrical formation constitutes a channel from the region of point C to the periphery, and which slopes opposite the general direction of air movement across the blade when in motion.

The third forming line CD which is somewhat shorter, by reason of its location, than the two described, lies at an angle preferably of the order of 30 degrees to the line CB, and bounds a channel presented on the back or intake face of the blade, resulting in a similar convexity presented on the pressure face of the fan. The relation between the ten inch positive curvature of area BCD, and the last noted negative curvature characterizing the area D-27-C on backward radii, best appears from the section of Fig. 6. The backward radii on which the latter area is formed, are preferably of the order of six inches. Thus the area D-27-C constitutes a portion of a cylinder of this radius. It will now have appeared that the several groups of forward and backward radii, as described, may be considered as ranged parallel to the forming lines, with those of each group considered as being in a row tangent to a circle on the axis of propeller revolution.

It will now have appeared that the concave region bounded by lines CB and CD consists of a relatively inverted triangular area which may be considered a trailing portion of the blade, and that the line CD taken with the trailing extremity of peripheral edge 26, and trailing edge 30,

forms a final quasi-triangular portion which may be considered as inverted, and which portion is as viewed, somewhat backwardly bent although preferably exhibiting some degree of positive pitch. The quasi-triangular portions in the order described are respectively designated at 31, 32, 33 and 34.

The main portion of each blade is that portion at the leading side of the line DC. It will be apparent that the said main portion of each blade beyond, or at the radially outward side of, the root area thereof is so formed that the pitch angles along each circular arc concentric with the axis of rotation, progressively increase in the trailing direction from the leading edge 24. The arc 7-7 in Fig. 1 may be taken as an example of a circular arc concentric with the axis of rotation, Fig. 7 being a sectional view taken along the said arc. By reference to Fig. 7 it will be observed that the pitch angles are progressively greater at the following zones spaced in the trailing direction: the zone immediately adjacent the leading edge 24, the zone midway between the leading edge 24 and the line BA, the zone between the lines BA and BC, the zone midway between the lines BC and DC, and the zone immediately adjacent and at the leading side of the DC. The pitch angles similarly increase progressively along each other arc concentric with the axis of rotation and beyond or spaced outwardly from the root area.

From the foregoing description it will be observed that the forwardly curved leading area 31 of the blade is preferably a cylindrical section which is tangent along the line AB to the central area 32. The line AB intersects a radial line through the center of the blade at a substantial angle with its outer end at the periphery and with its inner end at the leading edge. The forwardly curved area 33 of the blade is preferably a cylindrical section which is tangent along the line CB to the central area 32. The line CB intersects the said radial line through the center of the blade at an opposite substantial angle with its outer end at the periphery and with its inner end at the trailing edge. The central area 32 is preferably triangular and is also preferably flat or substantially flat.

When the main portion of the blade is formed with two cylindrical sections such as 31 and 33 which are tangent to an intermediate flat section such as 32 narrower at the periphery than at the root, the concavity of the main portion is different along different arcuate lines concentric with the axis of rotation. The extent of concavity decreases progressively from the periphery to the root region. For instance, a concentric arcuate line near the periphery intersects only a very narrow portion of the flat area 32 and the degree of concavity is substantial. A concentric arcuate line substantially nearer the center intersects a much wider portion of the flat area 32 and the degree of concavity along the last said line is considerably less. A concentric arcuate line through the points A and C intersects only the flat area 32 and there is no concavity.

The rearward curved trailing portion 34 joins the forward curved area 33 along the forming or juncture line CD. The outer end of the said line at D is substantially spaced in the trailing direction from a radial line through the center of the blade, that is, from a radial line through the point B. The line extends generally inward

from the point D and the inner end of the line at C is located at the trailing edge and is substantially spaced from the blade periphery. The portion 34 is bounded in part by an arc such as 27 which is tangent to the arcuate peripheral edge 26 and is also tangent to the radial trailing edge 30.

The particular blade formation as described has resulted from innumerable experiments followed by and including usual determinations of air stream movements, as by smoke streams and stroboscopic observation, and it may be here noted that the efficiency of the fan in comparison with a uniformly concave blade, is materially increased by addition of the channelling of the area 31. Similarly, advantages are offered by the channelling characterizing the area 33; however, a greatly improved performance is noted upon the introduction of both of these features of formation, and still further by the reversely curved trailing lip 34 resulting from the backward radii as described, the latter particularly serving to minimize, in fact virtually to prevent in a moderate speed fan, the adverse effect sometimes described as a tip vortex or eddy.

In presenting applicant's theory as to operation of a fan constructed and formed as described, it should first be noted that the design throughout is predicated upon what is herein for brevity and aptness, referred to as the air induction principle. Fundamental in this theory of operation is the use of a center disc or spider of a relatively small area, hence if circular, of a diameter which bears a low proportion to the diameter of the fan circle. It has been proven as a result of applicant's experiments that a propeller with a minimum center obstruction exhibits a relatively higher mechanical efficiency at low delivery pressures than comparable propellers with larger center discs or the like. Further, the provision, one example of which has been heretofore described, of a maximum practical open area around the hub region, has been shown to give a high mechanical efficiency through the low pressure range of the performance curve of the propeller. This range as heretofore implied, is that over which ventilating and attic fans will usually operate. Applicant's belief as to the reasons for or explanation of the high efficiency attained at low pressures is that the high-velocity tubular or annular stream emanating from approximately the outer one-third of the fan blades, results in a pressure drop or cavitation which effect is believed to be greatest on the front center of the fan. It now follows that, assuming the root regions of the blades to be mutually well spaced, and the center of the whole propeller of relatively open design, the higher pressure air on the intake side of the fan will be induced or drawn through such open area into the low pressure zone centrally of the pressure face, and will thereupon augment the volume of air positively impelled by the faster moving outer part, of the propeller. It is applicant's belief that such portion of the air delivery, namely, that part which is induced by flow into and about its center region, is attained with virtually little increase in power requirement, inasmuch as the energy necessary for such induction has theretofore been expended in the development of the velocity of the stream impelled by the outermost one-third (for example) of the fan circle. It is felt that this theory accounts for the rise in mechanical efficiency of the propeller. It is in

keeping with this principle that the center disc 10 is kept small, and blade angle is preferably at a maximum to provide greatest open area between the blades, which effect is further augmented by minimizing the width of the blade root regions.

The wide divergence between lateral blade margins conduces to a high air velocity in the peripheral region, at the same time obstructing no more than necessary, the induced central stream of air. The extreme divergence of leading and trailing margins presents the advantages of wide-blade fans, including quietness of operation.

By way of explanation of the advantages of the general formation of the blade as to its varying concavity and location of forming lines, it may be noted that the relatively large forward radii characterizing the area 31, give the effect of a substantially constant pitch to the leading area of the blade, and thus minimize drag losses on the outer portion thereof. Further, such forming results in the channelled section extending outwardly of the axis in the direction of rotation, this channel being of material aid in imparting a centrifugal effect to the induced air entering the blade, causing it definitely to rise on the blade. Such outward component of air motion persists until its radial force component is neutralized by the atmospheric pressure about the blade periphery, acting to impel the air into the low pressure zone created by axial velocity of the described tubular air stream.

As heretofore briefly noted, the channel beyond the forming line CB, being in area 33, and on a somewhat lesser radius than the leading area 31, provides additional axial velocity to the flow resulting from the actual air contact with the blade. This channel is sloped oppositely to that of area 31, and thus imparts a centripetal effect to the air, somewhat compensating the centrifugal action of area 31, and coacts with the air pressure about the periphery in forming and maintaining the tubular character of the fan stream.

The backwardly formed trailing area is an added feature of design for best results, and permits a smooth takeoff of the positively axially impelled air stream, and prevents all but a negligible minimum of turbulence loss or tip vortex, otherwise resulting in the recognized blade tip drag.

Tests indicate that the outer diameter of the annular or tubular velocity ring is substantially the same as the fan diameter, since the effect of ambient air pressure thereabout, serves thus to limit the outer diameter of this high velocity cylinder.

The induction theory heretofore described is upheld by the shape and pattern of the efficiency curve of propellers constructed substantially as described; such curve shows the highest efficiency in the region of zero static pressure and decreases only very little as static pressure is slightly increased, then diminishes rapidly with successive increases in static pressure. It is not intended that a propeller designed as described will exhibit high efficiency against high pressures, this being inherently inconsistent with the theory of a centrally induced flow, it being possible to attain such flow only within a low range of working pressures. It will, however, appear that a fan designed in keeping with the theory discussed, will realize the many advantages of propellers characterized by wide blades with off-radial channelling, and will serve fully to attain

each of the several objects hereinabove expressly stated and others implied from the structural description of a selected exemplary embodiment.

Although the invention has been described by specific reference to a single propeller of commercial type, the specification should not be understood in any limiting sense, inasmuch as numerous variants are possible within the scope of the appended claims.

10 I claim as my invention:

1. The combination in a fan, of a rotatable hub and a plurality of similar blades secured thereto at substantial pitch angles each of which blades is of uniform thickness, the main portion of each 15 blade beyond the root area thereof being generally concave at the pressure or forward side thereof and the leading and trailing areas of the said main portion beyond the said root area being forwardly curved sections tangent to a plane having a substantial pitch angle, the said leading forwardly curved section being tangent to the said plane along a line which intersects a radial line through the center of the blade at a substantial angle with its outer end at the periphery and with its inner end at the leading edge of the blade and the said trailing forwardly curved section being tangent to the said plane along a line which intersects the said radial line at a substantial angle with its outer end at the periphery and with its inner end terminating at the trailing edge of the blade.

2. The combination in a fan, of a rotatable hub and a plurality of similar blades secured thereto at substantial pitch angles each of which 35 blades is of uniform thickness, the main portion of each blade including a substantially flat triangular central section located at a substantial pitch angle and having its base at the root area of the blade and the said main portion of the blade also including two cylindrical sections at the leading and trailing sides of the triangular central section, which cylindrical sections are curved in the pressure or forward direction, the said leading cylindrical section being tangent to the said central section along the leading edge thereof and the said trailing cylindrical section being tangent to the said central section along the trailing edge thereof.

3. The combination in a fan, of a rotatable hub and a plurality of similar blades secured thereto at substantial pitch angles each of which blades is of uniform thickness and has an arcuate peripheral edge substantially concentric with the axis of rotation, each blade comprising a main portion and also comprising a trailing portion which is curved in the intake or rearward direction, the said main portion of each blade beyond the root area thereof being generally concave at the forward side and the leading and trailing areas of the said main portion beyond the root area being forwardly curved substantially cylindrical sections tangent to a plane having a substantial pitch angle, the said leading cylindrical section being tangent to the said plane along a line which intersects a radial line through the center of the blade at a substantial angle with its outer end at the periphery and with its inner end at the leading edge of the blade and the said trailing cylindrical section being tangent to the said plane along a line which intersects the said radial line at a substantial angle with its outer end at the periphery and with its inner end at the trailing edge of the blade, and the said rearward curved 70 trailing portion of each blade joining the said 75

main portion along a substantially straight juncture line which extends generally inward from an intersection point located at the said peripheral edge of the blade and substantially spaced in the trailing direction from a radial line through the center of the blade and which terminates at a second intersection point located at the said trailing edge of the blade and substantially spaced from the blade periphery.

4. The combination in a fan, of a rotatable hub and a plurality of similar blades secured thereto at substantial pitch angles each of which blades is of uniform thickness and has an arcuate peripheral edge substantially concentric with the axis of rotation, each blade comprising a main portion and also comprising a trailing portion curved in the intake or rearward direction and bounded in part by an arc of substantially uniform convex curvature tangent to the said arcuate peripheral edge and also tangent to the trailing edge of the blade, the said rearward curved trailing portion of each blade joining the said main portion along a substantially straight juncture line which extends generally inward from an intersection point located at the said peripheral edge of the blade and substantially spaced in the trailing direction from a radial line through the center of the blade and which terminates at a second intersection point located at the trailing edge of the blade and substantially spaced from the blade periphery.

5. The combination in a fan, of a rotatable hub and a plurality of similar blades secured thereto at substantial pitch angles each of which blades is of uniform thickness and has an arcuate peripheral edge substantially concentric with the axis of rotation, each blade comprising a main portion which is concave at the pressure or forward side thereof and also comprising a rearward curved trailing portion, the said main portion of each blade beyond the root area thereof being so formed that the pitch angles along each circular arc concentric with the axis of rotation progressively increase in the trailing
